UNITED STATES PATENT OFFICE

JOHN C. CHAMBERS, OF BRIDGEPORT, CONNECTICUT, ASSIGNOR TO ADDRESSOGRAPH COMPANY, OF WILMINGTON, DELAWARE, A CORPORATION OF DELAWARE

SAFETY DEVICE

Application filed December 15, 1930. Serial No. 502,296.

This invention relates to safety devices especially adaptable for use on printing machines and the like wherein a plurality of sheets are successively withdrawn from a supporting rack and sequentially passed through the machine.

The salient object of the invention is to provide a novel safety device engageable with the sheets in the supporting rack to prevent the withdrawal of more than one sheet at a time from said rack.

Another object is to provide a safety device that may be accurately positioned to ensure proper operation.

A further object is to provide a safety device which may be expeditiously mounted in position in a manner that will not in any way interfere with other portions of the machine.

A selected embodiment of the invention is illustrated in the accompanying drawing in which

Fig. 1 is a fragmentary elevational view of one end of a typical printing machine with which my invention is associated;

Fig. 2 is a view taken substantially on the line 2—2 of Fig. 1 and drawn to an enlarged scale;

Fig. 3 is a fragmentary detail view illustrating the operation of my safety device; and

Fig. 4 is a perspective view of the device.

In the accompanying drawing wherein a selected embodiment of the invention is illustrated, I have shown the invention associated with a printing machine of a character wherein the sheets are arranged in a rack located at one end of the machine.

The sheets are sequentially withdrawn from the rack and passed through the machine to be addressed or to have other operations performed thereon as, for example, if the sheets to be printed are checks they may be

passed through the machine to have a signature printed thereon. When the machine is used in this manner it is of utmost importance that each sheet or check passed through the machine have an impression made thereon but if two sheets are with-

drawn from the supporting rack and passed through the machine in superimposed relation one of the sheets will not receive an impression. To prevent this, I have provided a safety device which will so operate that but one sheet or check will be withdrawn from the machine upon each operation of the withdrawing means. A sheet supporting rack and withdrawing means of the character with which my invention may be advantageously associated is disclosed in the application of Walter T. Gollwitzer, Serial No. 497,440, filed in the United States Patent Office on November 22, 1930. As set forth in that application, a rack 5 is mounted at one end of the machine 6 and this rack includes a flat backing plate arranged to extend substantially vertically and this plate is preferably of less length than the sheets arranged therein so that the upper ends of the sheets will extend beyond the upper end of the plate as illustrated in Fig. 2. The sheets are held in engagement with the plate of the rack by a follower block 7 resting against the outermost of the sheets arranged in the rack between the side members 8, 8 thereof. Pivotally mounted at 9 on the frame of the machine is a link 10 carrying a sucker bar 11 having a plurality of nozzles 12 thereon. The sucker bar 11 is connected to a suitable air exhausting means and the nozzles thereon are movable into engagement with the sheet engaging the flat plate of the rack 5 as illustrated in dotted lines in Fig. 2. Therefore, since air is being drawn into the sucker bar 11 through openings in the nozzles 12, it is manifest that engagement of the nozzles 12 with the sheet will close the openings there-

in and thus a vacuum will be drawn which will cause the sheet to tightly adhere to the nozzles. The nozzles 12 are then moved into the full line position of Fig. 2 below the periphery of the feed roller 13 and as the nozzles pass below the periphery of the feed roller, the vacuum drawn into the sucker bar is broken and therefore the sheet will be released from the nozzles and at the time the vacuum is broken the clamping roller 14 will have been moved above the sheet

engaged with the periphery of the roller 13 to clamp said sheet against said roller and movement will be imparted to the roller to rapidly withdraw the sheet from the rack 5 and pass it into the machine. As the nozzles 12 move downwardly from the dotted line position of Fig. 2 into the full line position of said figure, the sheet is bent substantially as illustrated in dotted lines and as soon as the sheet has moved sufficiently to clear the line of movement of a retaining finger bar 15 it is moved from the dotted line position of Fig. 2 into the full line position thereof wherein it rests on the sheets remaining in the rack 5 to hold these sheets against movement when the sheet being withdrawn is moved by the action of the roller 13. While the sheets are picked up by pneumatic means, it may sometimes happen that more than one sheet will be picked up and to prevent this I have provided the safety device forming the subject matter of this invention and which includes the following mechanisms.

25 A bracket generally indicated by 16 is provided which includes a vertically extending arm 17 and a horizontally extending arm 18 having a threaded opening 19 therein. A substantially L-shaped bracket 30 is provided including an arm 21 having a slot 22 therein through which the screw 23 is passed and said screw is fitted into the threaded opening 19 to clamp the arm 21 to the arm 18. A bifurcated lug 24 is 35 provided on the arm 25 of the bracket 20 and in the bifurcation thereof the lug 27 on the pawl 28 is pivotally mounted on the pin 26. The pawl 28 includes a knife edge 29. In the arm 17 of the bracket 16 there is a slot 30 through which the stem of the thumb screw 31 is extended, said screw fitting in a threaded opening in the wall of the housing 32 of the machine 6. In use preferably two such devices are provided 40 which are arranged in side by side relation as illustrated in Fig. 1 and the devices are so disposed that the pawls 28 will engage the sheets on opposite sides of, but closely adjacent to, the center of the sheets. By 45 loosening the screw 23 the arm 21 may be adjusted along the arm 18 so that the knife edge 29 on the pawl 28 will be disposed relative to the upper edge of the sheets in the rack 5 to slightly bend the same in a direction away from the plate as illustrated in Fig. 2 when the pawl 28 is in normal position. The pawl 28 is held in this normal position by the spring 33 extending between spring anchors on the pawl 28 and the arm 25 and this spring urges the inner edge of the lug 27 into engagement with the bottom of the bifurcation in the lug 24 to determine the normal position of said pawl. Preferably the knife edge 29 of the pawl 28 will be disposed to extend a slight dis-

tance below the upper edges of the sheets and this is accomplished by loosening the screw 31 to permit the bracket 17 to be adjusted vertically, this being afforded by the slot 30. When the nozzles 12 grip a sheet and move the sheet outwardly, the pawl 28 will be pivoted about the pin 26 and the knife edge 29 thereof will drag over the upper edge of the sheet being moved by the nozzles 12 and will therefore effectively separate the sheets since the knife edge thereon will tend to move between the edge of the sheet being moved and the adjacent sheet in the rack.

80 Since the pawl is spring-urged into position and includes a knife edge, it is manifest that an effective separation of the sheets will occur. Moreover, the device is arranged so that it can be very accurately adjusted in order that it will properly engage the sheets to ensure separation thereof and it is therefore manifest that it will effectively perform its function as a safety device.

85 In the foregoing description I have set forth a selected embodiment of my invention but it is to be understood that this is capable of variation and modification and I therefore do not wish to be limited to the precise details set forth but desire to avail myself of changes and modifications falling within the purview of the following claims.

90 I claim:

95 1. In a printing machine which has a sheet supporting rack and means for withdrawing sheets therefrom, the combination of a safety device including a pivotally mounted member embodying a knife edge engageable with the edges of the sheets and yieldably urged into sheet engaging position and movable over said edges to ensure separation of said sheets so that the sheets will be withdrawn from said rack one at a time, means supporting said member, means providing adjustment of said supporting means whereby said member may be moved relative to the ends of said sheets, and means providing another adjustment of said supporting means whereby said member may be moved relative to the face of said sheets.

100 2. A safety device for ensuring the withdrawing of sheets from a supporting rack one at a time and including a member engageable with said sheets and movable over the edges thereof to ensure separation, means for securing said member in position and affording adjustment thereof toward and away from the ends of the sheets to be engaged thereby, and means affording adjustment of said member relative to the face of said sheets.

105 3. A safety device including an adjustably mounted bracket, a supporting member adjustably mounted on said bracket, a pawl pivotally mounted on said supporting mem-

ber, yieldable means for urging said pawl in a given direction, and means on said pawl and engageable with said supporting member for limiting the action of said yieldable means to determine the normal position of said pawl.

4. A safety device including a bracket, a supporting member adjustably mounted on said bracket and having a bifurcated lug, a pawl pivotally mounted in the bifurcation in said lug, a spring disposed between said pawl and said supporting member and acting on said pawl, and means for limiting the action of said spring.

15 5. A safety device including a bracket embodying a vertically extending arm and a horizontally extending arm, a substantially L-shaped bracket having one arm thereof slidably connected to the horizontally disposed arm of said first-named bracket and having a bifurcated lug on the other arm thereof, a pawl including a knife edge, means pivotally supporting said pawl in said bifurcation, and means positioning said pawl 25 in a predetermined position.

6. A safety device including a supporting

bracket, a substantially L-shaped bracket having one arm thereof adjustably connected to said supporting bracket, a bifurcated lug on the other arm of said L-shaped bracket, a pawl having a boss thereon disposed in 70 said bifurcation and pivotally connected to the parts defining said bifurcation, and a spring extending between said L-shaped bracket and said pawl and acting thereon to urge the end of said pawl on the side of 75 said boss opposite the side thereof engaged by said spring into a predetermined position.

7. A safety device including a supporting bracket, a substantially L-shaped bracket having one arm thereof adjustably connected to said supporting bracket, a bifurcated lug on the other arm of said L-shaped bracket, a pawl including a knife edge and having a boss thereon inwardly of said knife edge, 80 means pivotally connecting said boss and said bifurcation, and a spring extending between said L-shaped bracket and said pawl for urging the knife edge on said pawl into 85 a predetermined position.
